US0D1111688S

(12) **United States Design Patent** (10) **Patent No.:** **US D1,111,688 S**
(45) **Date of Patent:** **** Feb. 10, 2026**

(54) **CONTAINER**

(71) Applicant: **YETI Coolers, LLC**, Austin, TX (US)

(72) Inventors: **Dustin Bullock**, Austin, TX (US); **John Loudenslager**, Austin, TX (US); **John Fritz**, Austin, TX (US); **Michael Christopher Cieszko**, Austin, TX (US); **Andrew J. Winterhalter**, Austin, TX (US)

(73) Assignee: **YETI Coolers, LLC**, Austin, TX (US)

(**) Term: **15 Years**

(21) Appl. No.: **29/898,738**

(22) Filed: **Jul. 31, 2023**

Related U.S. Application Data

(63) Continuation of application No. 29/849,054, filed on Aug. 8, 2022, now Pat. No. Des. 997,650, which is a continuation of application No. 29/737,275, filed on Jun. 8, 2020, now Pat. No. Des. 959,918, which is a continuation of application No. 16/218,089, filed on Dec. 12, 2018, now Pat. No. 10,766,672.
